NIPPLE FOR NURSING BOTTLES

Filed Jan. 23, 1929

INVENTOR,
MERVYN C. LASKY.
BY Martin P. Smith ATTY.

UNITED STATES PATENT OFFICE

MERVYN C. LASKY, OF HOLLYWOOD, CALIFORNIA

NIPPLE FOR NURSING BOTTLES

Application filed January 23, 1929. Serial No. 334,510.

My invention relates to a nipple for nursing bottles and has for its principal objects the provision of a relatively simple and inexpensive nipple having an outlet opening that cannot be closed as a result of pressure on the nipple while the same is in use, further to provide a nipple that will insure a constant and uniform flow of liquid through the outlet opening or orifice while said nipple is in use, and further to provide a nipple of the character referred to that may be readily cleansed and maintained in a sanitary condition.

Ordinary nursing bottles are formed of rubber or rubber composition and when pressure is applied to the nipple by the nursing infant it very frequently happens that the outlet aperture becomes closed, or partially closed, so as to interrupt the constant flow or discharge of liquid from the nursing bottle and it is one of the objects of my invention to provide a relatively simple arrangement in the nature of a reinforcement for the outlet opening of the nipple for eliminating the defects just noted.

With the foregoing and other objects in view, my invention consists in certain novel features of construction and arrangement of parts that will hereinafter be more fully described and claimed and illustrated in the accompanying drawings, in which:

Fig. 1 is a perspective view of a nipple constructed in accordance with my invention.

Fig. 2 is a perspective view of the reinforcing member that is arranged in the outlet opening of the nipple.

Fig. 3 is an enlarged cross sectional view taken approximately on the line 3-3 of Fig. 1.

Fig. 4 is a sectional view similar to Fig. 3, and showing a modified construction of the nipple.

Fig. 5 is a sectional view similar to Figs. 3 and 4 and showing a further modified form of the nipple.

Referring by numerals to the accompanying drawings which illustrate a practical embodiment of my invention, 10 designates the body of the nipple which is of the usual form and molded or constructed from rubber or

rubber composition, the base or lower portion of the nipple body being enlarged so as to be fitted onto the neck of the nursing bottle.

Formed in the apex or upper end of the nipple is the usual outlet aperture 11, and in accordance with my invention there is imbedded in the upper body of the nipple immediately adjacent to its opening a disk 12 which is preferably concavo-convex in shape in order to conform to the curvature of the body of the nipple adjacent to the outlet aperture.

Formed in the disk 12 are apertures 13, and when the disk is inserted in the nipple during the process of manufacture, a portion of the rubber fills these apertures, thereby very firmly anchoring the disk in the nipple body at the desired point.

Formed integral with the central portion of the disk 12 is a small inverted cup-shaped member 14 that projects upwardly through the upper portion of the outlet aperture 11 and the top 15 of the member 14 lies flush with the outer surface of the apex or upper end of the nipple body.

Formed in the top 15 of the member 14 are relatively small apertures 16 through which the fluid passes while the nipple is in service.

Disk 12 and the inverted cup-shaped member 14 are preferably formed of non-corrodible metal, for instance gold or gold-plated base metals, and in some instances said disk and member may be formed of material such as celluloid or hard rubber.

In Fig. 4 I have illustrated a construction wherein a short tubular member 17 of non-corrodible metal or material such as rubber or celluloid is removably arranged in the aperture in the end of the nipple and formed on the lower end of this tubular member is a flange 18 that fits snugly against the inner surface of the wall of the nipple around the outlet aperture.

Formed integral with the outer end of the tubular member 17 is a perforated disk 19 and the edge thereof is extended slightly beyond the tubular wall of the member 17 to form a flange 20 that overlies the outer surface of the body of the nipple adjacent to the opening therethrough.

The member 17 and parts 18 and 19 are preferably formed from a single piece of non-corrodible metal or from material such as celluloid or hard rubber, and this form of device is adapted to be readily inserted through or removed from the aperture in the apex or upper end of the nipple body. Owing to the relative sizes of the flange 18 and the opening in which the tubular body 17 is seated, it is impossible for the member 17 to be drawn outwardly from the nipple.

In the modified construction illustrated in Fig. 5, a plug 21 of hard rubber or analogous material is seated in the upper end or apex 15 of the body of the nipple 20 and vulcanized thereto, and said plug being provided with a series of apertures 22 which function as outlet openings for the fluid while the nipple is in service.

Thus it will be seen that I have provided a nipple having an outlet aperture or apertures that cannot be closed, or partially closed, as a result of pressure upon the nipple while the same is in service, and said apertures being formed in relatively hard material so as to insure a constant flow of fluid from the nipple.

The fluid flow controlling member that is seated in the nipple in no wise interferes with 30 the nursing operations, but on the other hand provides for a constant flow of a predetermined volume of fluid from the nipple while the same is in service, and the inserted member is non-corrodible and may be very readily 35 cleansed with the nipple and therefore maintained in a sanitary condition.

It will be understood that minor changes in the size, form and construction of the various parts of my improved nipple for nursing 40 bottles may be made and substituted for those herein shown and described without departing from the spirit of my invention, the scope of which is set forth in the appended claim.

I claim as my invention:

A nursing bottle nipple, comprising a nipple body formed of elastic material and provided at its tip with an opening, an inverted cup-shaped member of inflexible material imbedded in the tip of the nipple above said opening, the chamber within which cup-shaped member and the opening in the tip of the nipple having the same diameter so as to provide a continuous chamber having a smooth inner surface, the top plate of said inverted cup-shaped member being provided with a plurality of apertures, the outer surface of which perforated top plate is flush with the outer surface of the tip of the nipple, a downwardly curved flange integral 50 with the lower edge of the circular wall of the inverted cup-shaped member, the curvature of which flange coincides with the curvature of the wall in the apex portion of the nipple body, said flange being imbedded in 60 the wall of the apex portion of the nipple.

body around the opening therein and which flange is provided with apertures that are occupied by the elastic material of which the nipple body is formed.

In testimony whereof I affix my signature.

MERVYN C. LASKY.
